TOY CLOWN BANK

Leonard Florence, Revere Beach Parkway, Chelsea, Mass.

Filed Nov. 14, 1961, Ser. No. 67,515

Term of patent 14 years

(Cl. D34—11)

I claim:

The ornamental design for a toy clown bank, as shown.
